CONTROL OF STEAM TEMPERATURE

John D. Kuppenheimer, Worcester, Mass., assignor to Riley Stoker Corporation, Worcester, Mass., a corporation of Massachusetts

Application January 18, 1950, Serial No. 139,167

6 Claims. (Cl. 122—479)

1

This invention relates to the control of steam temperature, and more particularly to an apparatus for controlling the temperature of steam leaving a superheater.

It is one object of the invention to provide a simple and inexpensive apparatus whereby the temperature of steam leaving a superheater may be maintained at a desired value.

It is a further object of the invention to provide an apparatus for steam temperature control which will not contaminate the steam.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts.

Fig. 1 is a longitudinal section through the upper portion of a steam generator;

Fig. 2 is an enlarged view of a portion of Fig. 1;

Fig. 3 is a section taken on the line 3—3 of Fig. 2; and

Fig. 4 is an enlarged view of a portion of Fig. 2.

The embodiment illustrated includes a steam generator comprising a horizontal elongated cylindrical steam-and-water drum 10, water tubes 11 associated with the drum, a superheater 12 to receive steam from the drum, a superheater outlet header 14, a combustion chamber 15, a gas outlet duct 16, and gas-directing baffles 18. It will be understood that a suitable fuel will be burned in the combustion chamber 15 to provide hot gases which will heat the various water tubes and generate steam therein. The gases will escape through the duct 16, and the steam will be released in the drum 10. Tubes 19 are arranged in a longitudinally extending row along the drum 10 to conduct steam therefrom to the superheater 12.

Within the upper portion of the drum there is provided a steam passage 21 having a bottom wall 22 and end walls 23 (only one being shown). The inlet ends of the tubes 19 communicate with the front portion of this passage to receive steam therefrom. In entering the passage 21 from the lower portion of the drum, the steam is compelled to flow through moisture separating apparatus 25 located in the rear portion of the passage. One suitable construction for the apparatus 25 is disclosed in the prior patent to Kuhnner No. 2,235,892, granted March 25, 1941. The bottom wall 22 is shaped to provide a trough 27 which lies in front of the separator 25 and extends lengthwise of the drum. A J-shaped pipe 28 extends downwardly from the trough 27 to provide a drainage trap, the lower end of this pipe having a disk 29 resting thereon to form a check valve, this disk being free to move vertically within a guiding cage 30.

2

With the construction as so far described, the temperature of the superheated steam reaching the steam outlet header 14 will vary with changes in the demand for steam, changes in the type of fuel used, or from other causes. In order to minimize such variations in steam temperature I maintain a suitable control over the moisture content of the steam leaving the drum 10. If the steam temperature increases slightly I increase the moisture content and vice versa. For this purpose two parallel horizontal pipes 32 are mounted one above the other within the passage 21 and extend lengthwise of the drum. These pipes extend through the end walls 23 and they may be closed at one end, the other ends being joined and connected by a union 33 (Fig. 3) to a pipe 34 extending through one end of the drum 10. A pipe 35 is connected to the outer end of the pipe 34. The portions of the pipes 32 located within the chamber 21 are provided with orifices 37 and they are surrounded by porous material 38 which is preferably of a fibrous nature, such as stainless steel wool, glass wool, or the like.

The porous material 38 surrounding each pipe 32 is preferably of airfoil shape, and in the embodiment illustrated it is provided with a blunt or rounded "leading" edge facing the on-coming stream, convex lateral surfaces, and a relatively thin "trailing" edge. This shape as shown is symmetrical about a plane passing through the axis of the pipe 32 and extending parallel with the general direction of flow of the steam as it travels from the separating apparatus 25 to the tubes 19. For convenience in installation the porous material 38 is preferably pressed or otherwise formed into separate bats of appropriate length, each bat having one flat side which conforms with the plane of symmetry of the airfoil shape. In order to prevent the bats from turning about the pipes 32, each of these pipes carries two rows of studs 40 located on opposite sides of the pipe and lying in the plane of symmetry. The blunt leading edge of each airfoil is protected by a metal strip 41 of arcuate cross-section, and the trailing edge is protected by a metal strip 42 of V cross-section. The strips 41 and 42, and the bats of porous material 38 are held in place by means of metal wires 44 which are wrapped around these parts and their ends then twisted together (Fig. 4).

Relatively pure water, for example a portion of the boiler feed water, is supplied to the pipe 35 at a pressure somewhat above the boiler steam pressure, and the flow through this pipe is controlled by a valve 46 of the well-known diaphragm-operated type having a diaphragm chamber 47. This chamber 47 is connected by a pipe 48 to a suitable relay 50 which is connected by a pipe 51 to a thermostatic bulb 52 located in the superheater outlet header 14. Air or other fluid under pressure is supplied to the relay 50 through a pipe 54. This relay is of a well-known

type arranged to vary the pressure in the diaphragm chamber 47 in accordance with changes in the temperature to which the bulb 52 is subjected. Preferably a manually operable valve 55 is mounted in a by-pass line 56 around the valve 46.

The operation of the invention will now be apparent from the above disclosure. Steam will be generated in the water tubes 11 and released in the drum 10. The steam will then flow through the separator 25, which will remove moisture therefrom, and thence forwardly past the porous material 38 and into the tubes 19 leading to the superheater 12 and the outlet header 14. The by-pass valve 55 will be closed, and water will flow through the pipe 35 under the control of the diaphragm valve 46, into the pipes 32, and through the perforations 37 into the porous material 38. As the steam flows over the convex lateral surfaces of the porous material 38 the pressure of the steam will be slightly reduced, and some of the water held by the material 38 will evaporate into the steam, somewhat increasing the moisture content of the steam. So long as the temperature of the superheated steam reaching the outlet header 14 remains at the desired value, no adjustment of the valve 46 will take place. If however the steam temperature increases even very slightly, the temperature responsive bulb 52 will respond to such increase and affect the relay 50 so that the pressure transmitted through the pipe 48 to the diaphragm chamber 47 will be varied as required to open the valve 46 slightly. This will supply more water to the pipes 32 and to the porous material 38, more moisture will be evaporated from this material into the steam, thereby increasing the moisture content of the steam entering the superheater 12, and the steam temperature at the outlet header 14 will be restored to the desired value. Similarly, if the steam temperature becomes too low, the valve 46 will be actuated to reduce the supply of water to the porous material 38, the moisture content of the steam entering the superheater 12 will be decreased, and the temperature of the steam entering the header 14 will be raised. Thus an accurate control of the steam temperature will be maintained automatically.

Since the moisture is added to the steam by the evaporation of water supplied through the pipe 35, any dissolved or suspended foreign matter carried by this water will be deposited in the porous material 38, rather than injected into the steam to contaminate the same. Accumulations of such matter may be removed from the material 38 by opening the by-pass valve 55 for a brief interval to provide a large momentary flow of water through the pipes 32, thereby flushing the foreign matter out of the material 38 and into the trough 27, whence it will escape through the trap 28 into the boiler water. During this operation the boiler should preferably be relieved of all or most of its load. Such flushing of the material 38 will seldom be required unless the water supply contains considerable foreign matter.

It will be recognized that the invention provides a new and highly advantageous apparatus whereby the temperature of superheated steam may be accurately controlled.

Having thus described my invention, what I claim as new and desire to secure by Letters Patent is:

1. In combination with an elongated cylindrical

drum having a longitudinal row of steam outlets therein and a passage for the flow of steam in a direction substantially perpendicular to the longitudinal axis of the drum to the outlets, a superheater connected to the outlets to receive steam therefrom, a pipe located within the passage and extending lengthwise of the drum, the pipe having orifices therein, a body of porous material enclosing the pipe and shaped as an airfoil so that the pressure of the steam flowing over the surfaces of the body will be slightly reduced, means to supply water to the pipe for discharge from the orifices thereof into the porous material and evaporation by the steam, and means to increase the rate of water supply as the temperature of the steam leaving the superheater increases and vice versa.

2. Apparatus as set forth in claim 1, in which the body of porous material is provided with a blunt leading edge facing the on-coming steam and with a trailing edge which is relatively sharp compared with the leading edge.

3. Apparatus as set forth in claim 2, in which the blunt leading edge is protected by a metal strip of arcuate cross-section, and the sharp trailing edge is protected by a metal strip of V cross-section.

4. Apparatus as set forth in claim 1, in which the body of porous material is formed of separate bats located on opposite sides of a plane passing through the axis of the pipe and extending parallel with the general direction of flow of the steam in the passage, the body being substantially symmetrical about the said plane.

5. Apparatus as set forth in claim 4, in which the pipe carries two rows of projecting studs located on opposite sides of the pipe and lying in the plane of symmetry.

6. In combination with an elongated cylindrical drum having a longitudinal row of steam outlets therein and a passage for the flow of steam substantially perpendicular to the longitudinal axis of the drum to the outlets, a superheater connected to the outlets to receive steam therefrom, a pipe located within the passage and extending lengthwise of the drum, the pipe having orifices therein, a body of porous material enclosing the pipe so that the pressure of the steam flowing over the surfaces of the body will be slightly reduced, means to supply water to the pipe for discharge from the orifices thereof into the porous material and evaporation by the steam, and means to increase the rate of water supply as the temperature of the steam leaving the superheater increases and vice versa.
